UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

STEAM-TURBINE AND GOVERNOR.

1,397,086.

Specification of Letters Patent.

Patented Nov. 15, 1921.

Original application filed August 20, 1919, Serial No. 318,651. Divided and this application filed May 21, 1920. Serial No. 383,134.

To all whom it may concern:

Be it known that I, CHARLES W. DAKE, a citizen of the United States, residing at Chicago, in the county of Cook and State of Illinois, have invented a certain new and useful Improvement in Steam-Turbines and Governors, of which the following is a specification, said application being a division of my application filed August 20, 1919, Serial Number 318,651.

My invention relates to improvements in steam turbines and is a divisional application embodying the subject matter divided out of patent application Serial Number 318,651, filed August 20, 1919.

One object of my invention is to provide a new and improved form of steam turbine which will be light, self-contained, fool proof and easy to manufacture. Another object is to provide a turbine which will have a high economy and efficiency. Another object is to provide a turbine which will require a minimum of adjustment, change and reconstruction in operation. Other objects will appear from time to time in the specification.

My invention is illustrated more or less diagrammatically in the accompanying drawings wherein:

Figure 1 is a section in a horizontal plane with parts broken away;

Fig. 2 is a section along the line 2 2 of Fig. 1;

Fig. 3 is a section along the line 3 3 of Fig. 1;

Fig. 4 is a sectional view of the rotor;

Fig. 5 is an enlarged view of the governor weight;

Fig. 6 is a view of the buckets.

Like parts are indicated by like characters throughout the drawings.

A is a cylindrical motor generator housing having cast integral therewith a flat supporting base, A¹. This cylindrical housing is open at both ends and contains intermediate its ends a web A², having a central annular opening A³. A⁴ is a steam chamber within the web A² provided with a steam inlet passage A⁵, and communicating with a nozzle A⁶. This nozzle A⁶ is placed in a tube A⁷ which is introduced together with the nozzle in a bore in the web. The tube and nozzle are introduced through an opening in the cylinder which is closed by the

plug A⁸. A⁹ is the nozzle block in which the nozzle opening proper is formed.

B is an annular exhaust chamber about the periphery of the housing, bounded on one side by the web A² and on the other side by the rib B¹ which partially closes it. The exhaust chamber is enlarged at B³ and communicates with the exhaust pipe B⁴ and a drain pipe B⁵. B⁶ is a removable turbine wall positioned upon the rib B¹. It is parallel with the web A² and with it unites to make the turbine housing proper within which the turbine wheel is located. This turbine wall has a plurality of outwardly projecting arms B⁷ which are engaged by the bearing housing support B⁸. This bearing housing support is held seated against the rib B⁹ by the screw threaded turbine end closure B¹⁰. This bearing support is rigidly seated on the rib and the same is true of the turbine end wall. This is possible because the elasticity of the turbine end wall itself makes it safe to seat both snugly and firmly on their seats and any distortion caused by temperature changes will be taken care of by elasticity of the turbine wall.

Since the bearing assemblies at either end of the apparatus are identical a description of one will suffice for both. The bearing assembly is mounted on the support B⁸, which is flanged and provided with spaced webs G supporting a cylindrical member G¹. The flange is cut away as at G² so that no matter where it is placed it may come into register with the passage G³ which is supplied with oil by a passage G⁴ from the oil well G⁵, thus it makes no difference in what position the bearing support is placed since lubrication is always assured. G⁶ is a sleeve projecting inwardly from the plate G⁷, it is flanged as at G⁸ and carries the bearing G⁹ held in position therein by a spring ring G¹⁰.

D is a solid stub shaft having a reduced end D¹ supported in the ball bearing G⁹. D² is a sleeve on such reduced end adapted in coöperation with a nut D³ to hold the bearings and stub end shaft in proper operative position. D⁴ is an oiling plate fixed on the shaft and having its lower edge immersed in the lubricating oil. D⁵ is a hollow sleeve rigidly attached to the stub end shaft and extending from it toward the other end of the apparatus. It terminates just short

of a similar bearing G^9 at the generator end and is closed by hollow plug D^6 which plug is reduced to engage such bearing G^9 so that we have a rigid shaft fixed in position and held against longitudinal movement comprising a solid stub end shaft a sleeve and a hollow plug, the outside diameter of the sleeve and the stub being the same so as to give in effect a smooth and continuous outer shaft surface. The sleeve D^5 is slotted at D^7 and contains a plug D^8 having pins D^9 extending through longitudinal slots D^7 . This plug engages at one end a coiled spring D^{10} located within the hollow portion of the shaft. The other end of this spring is anchored on a plug D^{11} which is slideable within the shaft and may be adjusted in position by the screw D^{12} which extends out through the hollow plug D^6 so that a screw driver engaging the slotted head of the screw D^{12} can change the tension on the spring D^{10} and this tension is the tension which controls and regulates the governor as will hereafter be described.

E is a sleeve slidably mounted on the shaft, it is engaged by the pins D^9 so that the spring D^{10} may control the sleeve and provide a yielding resistance to the longitudinal movement thereof and at the same time the pins themselves hold the sleeve against rotation with respect to the shaft. At either end of the sleeve are collars E^4 closing the oil chamber and having flared oiled discharging ends so arranged as to discharge any oil which leaks toward the electrical or steam portion of the apparatus away from the bearings back into the bearing chambers. E^5 is a rotor disk. It carries the bucket wheel rim E^6 upon which are the buckets E^{16} joined together by the shroud E^7 . E^8 is a ring adapted to reinforce the bucket rim and assist in positioning the parts as hereafter explained, E^9 are a series of bent governor weights having outwardly extending knife edges which engage the ring E^8 at its engagement with the plate E^5 , spacing blocks E^{10} hold these governor weights in position. They extend inwardly down through the sleeve E and engage pockets E^{11} in the solid portion of the shaft. Their shape is such that when centrifugal force is exerted by them as the rotor turns they tend to rotate outwardly about their knife edges, and the result is that the central sleeve, the electrical rotor and the turbine are all moved to the left, because since the pivot point cannot move without moving the whole apparatus and since the base point is fixed on the main shaft that is the only movement that is possible. This movement is the movement which is resisted by the governor spring. E^{12} is a driving pin. It extends clear through the shaft and is anchored at either end on the turbine rotor. The ring E^{10} is slotted at E^{13} to permit this pin to move

with respect to the turbine so that the pin is able to take the driving load out at the periphery of the turbine leaving all the other parts free to give as the governor controls and moves them. This movement of the turbine to one side, of course, tends to bring the bucket and steam nozzle more or less out of register, and it is this movement that causes the turbine itself to serve as a valve, the shroud moving over and covering the nozzle and decreasing the steam supply, to control and regulate the speed.

It will be evident that while I have shown in my drawings an operative device, still many changes might be made both in size, shape, and arrangement of parts without departing materially from the spirit of my invention, and I wish therefore that my drawings be regarded as in a sense diagrammatic.

The use and operation of my invention are as follows:

Oil is poured into the oil pocket until the oil reaches such a level that the conveying disks at either end are immersed for an inch or so at the bottom. The apparatus is then sent out and set up on a locomotive, the steam and exhaust lines being connected up in the usual manner. As soon as the steam is turned on the buckets are engaged by the moving column of steam and the turbine is rotated. The steam continues to rotate the turbine until a predetermined speed is reached when the centrifugal force of the governor weight tends to move the outer shell or sleeve including the turbine and the electrical rotor longitudinally against the yielding resistance of the governor spring. This movement brings the shroud more or less into register with the steam nozzle and cuts off or controls the flow of steam. As the speed drops down the centrifugal force of the governor weights decreases and the governor spring tends to move the buckets back into line with the nozzle. Thus governing takes place in the usual manner.

In the form of structure which I have here shown, my turbine wheel takes the form of a hollow box like cylinder in which the governor weights are mounted and thus these parts are not only compactly arranged but they can be thoroughly lubricated. I have also in this structure shown the other parts of the governor as arranged within a hollow shaft which in like manner results in a compact arrangement of the parts and an easy method of lubrication. Both of these arrangements are included in the one structure here shown but either set of parts could be arranged otherwise and yet associated with a set of parts arranged as here shown. This arrangement of the parts also eliminates all windage or friction caused by the motion of the governor parts in a surrounding medium. The governor weight holding

the cylinder and the shaft, constitutes inclosed chambers so that the parts within them, together with the media which they contain, are rotated together. This cylinder and hollow shaft are also during operation, more or less filled with lubricant.

The governor may be conveniently divided for the purpose of consideration hereinafter, into two parts, governor weights 10 part and the tension part. The governor weights are acted upon by the centrifugal force and the tension part is that portion of the governor device which opposes the action of the governor weights.

15 The nozzle is brought to within five one thousandths of an inch of the surface of the wheel into which it is discharging so that in effect when the wheel is shifted, it reduces the effective opening of the nozzle and actually tends to shut off the steam without any appreciable leakage. Thus the method 20 of governing here illustrated, is free from objectionable waste of steam.

The wheel preferably has widely extended 25 surfaces on the sides of the bucket and the nozzle is placed in opposition to the bucket openings and such surfaces, so that when the wheel is shifted, the cutting off or reducing of the effective opening of the nozzle 30 is brought about.

The lubricant which is thrown up by the oil disk, gathers on the top of the interior surface of the end of the casing and is deflected over onto the upper outer wall of the 35 inner oil chamber proper, flows down the surface of the same into the ball bearing, works its way into and thence out of the inner oil chamber so as to maintain to a certain extent, a certain amount of oil through 40 the ball bearing.

The turbine wheel is connected with the shaft by means of a transverse pin which passes through the shaft to the outer periphery of the inner face of the wheel and here the two ends are received into slots formed within the wheel so that as the wheel rotates, it carries the shaft by means of engagement with the pin and the slots permit the wheel to slide rotatably with the shaft. 45 This motion develops friction between the pin and that portion of the wheel with which it engages and to reduce this friction to a minimum, this pin or its two extremities are extended as far as possible outwardly from the shaft. In other words, the driving connection between the wheel and the shaft is made as far as possible from the axis of the shaft.

The lubricant inserted in the exterior casing 50 is carried by the conveying disk upward and otherwise distributed so that it flows into the bearings and finds its way between the sleeve and a central cylindrical shaft until it supplies lubricant to the chamber

within the shaft which contains the tension device. It may pass also between the shaft and the sleeve into the governor weight chamber. The connection is substantially the same with reference to each end of the machine. Thus the bearing and sliding 65 parts are lubricated and the governor parts and the two governor chambers are lubricated. The generator chamber is, however, not thus exposed directly to the oil and this chamber is relatively free from oil. 70 75

I claim:

1. In a governor two members mounted for rotation together and slidably one on the other, governor weights comprising bent bars engaging one member at one end and 80 the other member at the other, and engaging said members in different parallel planes perpendicular to the axis of rotation, the weights tending to move such members with respect to one another laterally as the 85 weights tend to position themselves under centrifugal force in a plane perpendicular to the axis.

2. A governor comprising a rotary housing, a shaft upon which it is slidably mounted, governor weights loosely positioned within the housing engaging the shaft at one end and housing at the other, and inclined to a plane perpendicular to the axis 90 of rotation. 95

3. A steam turbine comprising a governor, a box-like cylindrical turbine wheel, governor weights contained therein, and a hollow shaft containing all the remaining parts of the governor. 100

4. A steam turbine comprising a box-like cylindrical turbine wheel, a hollow shaft, and governor parts and governor adjusting means which are entirely inclosed within the cylinder and shaft. 105

5. A steam turbine comprising a turbine wheel, a shaft and a governor, all the governor parts and governor adjusting means being entirely inclosed within the wheel and shaft. 110

6. A steam turbine comprising a turbine wheel, a shaft and a governor, all the governor parts being entirely inclosed within the wheel and shaft, means for adjusting the governor without the exposure of any 115 of the governor parts.

7. A steam turbine comprising a turbine wheel, a shaft and a governor, all the governor parts being entirely inclosed within the wheel and the shaft, the governor having a spring and means for adjusting the tension thereon without exposing any of the governor parts. 120

8. A steam turbine comprising a turbine wheel, a shaft and a governor, all the governor parts being entirely inclosed within the wheel and shaft, the governor having a spring located within the shaft and means 125

accessible through the end of the shaft for adjusting the tension on the governor spring.

9. A steam turbine comprising a turbine wheel, a shaft and a governor, all the governor parts being entirely inclosed within the wheel and shaft, means for adjusting the governor without the exposure of any of the governor parts, said means comprising a socket extending longitudinally through the shaft and terminating at the end thereof.

10. A steam turbine comprising a turbine wheel, a shaft and a governor, all the governor parts being entirely inclosed within the wheel and shaft, the governor having a spring and means for adjusting the tension thereon without exposing any of the governor parts, said means comprising a socket extending longitudinally through the shaft and terminating at the end thereof.

11. A steam turbine comprising a turbine wheel, a shaft and a governor, all the governor parts being entirely inclosed within the wheel and shaft, the governor having a spring located within the shaft and means accessible through the end of the shaft for adjusting the tension on the governor spring, said means comprising a socket extending longitudinally through the shaft and terminating at the end thereof.

12. A steam turbine comprising a turbine wheel, a shaft and a governor, the governor weights entirely inclosed in the wheel and the remaining governor parts entirely inclosed in the shaft, and means for adjusting the governor and without the exposure of any of the governor parts.

13. A steam turbine comprising a turbine wheel, and a hollow shaft which passes therethrough, and a governor, the governor parts inclosed entirely within the wheel and shaft, the adjusting parts of the governor being located in the shaft.

14. A steam turbine comprising a turbine wheel, and a hollow shaft which passes therethrough, and a governor, the governor parts inclosed entirely within the wheel and shaft, and means for adjusting the governor without exposing any of its parts.

15. A steam turbine comprising a turbine wheel, and a hollow shaft which passes therethrough, and a governor, the governor parts inclosed entirely within the wheel and shaft, the interior and exterior of the wheel and the hollow shafts so connected that lubricant may pass from one to the other.

16. A steam turbine comprising a turbine wheel and a shaft, and a governor, the governor weights inclosed within the wheel and fulcrumed on the shaft and the remaining governor parts inclosed within the shaft.

17. In a steam turbine, a governor comprising governor weights and a tension device, the latter suspended so that its mov-

ing part has no frictional engagement with any other part.

18. A steam turbine comprising a turbine wheel and a hollow shaft, and governor weights inclosed in the turbine wheel, and the tension device of the governor inclosed in the shaft and free from frictional contact with other parts.

19. A governor comprising governor weight parts, tension devices and a hollow shaft which incloses such tension devices, the latter arranged on the axis of the shaft.

20. A governor comprising governor weight parts, tension devices and a hollow shaft which incloses such tension devices, the latter arranged on the axis of the shaft and out of frictional contact with the other parts.

21. A steam turbine comprising a smooth shaft, a hollow drum like rotor mounted thereon having a smooth cylindrical surface, a cylindrical flange projecting laterally from one of the surfaces of the drum and in line with the periphery thereof and turbine buckets disposed within the flange whereby the motive fluid passes radially through said flange.

22. A steam turbine comprising a smooth shaft, a drum shaped rotor mounted thereon having a smooth cylindrical surface, a cylindrical flange projecting laterally from one of the surfaces of the drum and in line with the periphery thereof and turbine buckets disposed within the flange whereby the motive fluid passes radially through said flange, a sleeve on the shaft carrying the drum and mounted to slide with the drum along the shaft but held against rotational movement with respect thereto.

23. A steam turbine comprising a turbine wheel, a shaft and a governor, the governor being adapted to move the wheel laterally to control the steam flow, and all the governor parts being entirely inclosed within the wheel and shaft.

24. A steam turbine comprising a turbine wheel, a shaft and a governor, the governor being adapted to move the wheel laterally to control the steam flow, and all the governor parts being entirely inclosed within the wheel and shaft, means for adjusting the governor without the exposure of any of the governor parts.

25. A steam turbine comprising a turbine wheel, a shaft and a governor, the governor being adapted to move the wheel laterally to control the steam flow, and all the governor parts being entirely inclosed within the wheel and shaft, the governor having a spring and means for adjusting the tension thereon without exposing any of the governor parts.

26. A steam turbine comprising a turbine wheel, a shaft and a governor, the governor

- being adapted to move the wheel laterally to control the steam flow, and all the governor parts being entirely inclosed within the wheel and shaft, the governor having a 5 spring located within the shaft and means accessible through the end of the shaft for adjusting the tension on the governor spring.
27. A steam turbine comprising a turbine 10 wheel, a shaft and a governor, the governor being adapted to move the wheel laterally to control the steam flow, and all the governor parts being entirely inclosed within the wheel and shaft, means for adjusting the governor 15 without the exposure of any of the governor parts, said means comprising a socket extending longitudinally through the shaft and terminating at the end thereof.
28. A steam turbine comprising a turbine 20 wheel, a shaft and a governor, the governor being adapted to move the wheel laterally to control the steam flow, and all the governor parts being entirely inclosed within the wheel and shaft, the governor having a 25 spring and means for adjusting the tension thereon without exposing any of the governor parts, said means comprising a socket extending longitudinally through the shaft and terminating at the end thereof.
29. A steam turbine comprising a turbine 30 wheel, a shaft and a governor, the governor being adapted to move the wheel laterally to control the steam flow, and all the governor parts being entirely inclosed with- 35 in the wheel and shaft, the governor having a spring located within the shaft and means accessible through the end of the shaft for adjusting the tension on the governor spring, said means comprising a socket ex- 40 tending longitudinally through the shaft and terminating at the end thereof.
30. A steam turbine comprising a turbine wheel, governor weights entirely inclosed therein, a shaft and a governor spring en- 45 tirely inclosed therein.
31. A steam turbine comprising a turbine wheel, governor weights entirely inclosed therein, a shaft and a governor spring en- 50 tirely inclosed therein, means for adjusting the governor without the exposure of any of the governor parts.
32. A steam turbine comprising a turbine wheel, governor weights entirely inclosed therein, a shaft and a governor spring en- 55 tirely inclosed therein, the governor having a spring and means for adjusting the tension thereon without exposing any of the governor parts.
33. A steam turbine comprising a turbine 60 wheel, governor weights entirely inclosed therein, a shaft and a governor spring en- tirely inclosed therein, the governor having a spring located within the shaft and means accessible through the end of the shaft for adjusting the tension on the governor 65 spring.
34. A steam turbine comprising a turbine wheel, governor weights entirely inclosed therein, a shaft and a governor spring en- tirely inclosed therein, means for adjusting 70 the governor without the exposure of any of the governor parts, said means comprising a socket extending longitudinally through the shaft and terminating at the end thereof.
35. A steam turbine comprising a turbine 75 wheel, governor weights entirely inclosed therein, a shaft and a governor spring en- tirely inclosed therein, the governor having a spring and means for adjusting the tension 80 thereon without exposing any of the governor parts, said means comprising a socket extending longitudinally through the shaft and terminating at the end thereof.
36. A steam turbine comprising a turbine 85 wheel, governor weights entirely inclosed therein, a shaft and a governor spring en- tirely inclosed therein, the governor having a spring located within the shaft and means accessible through the end of the shaft for 90 adjusting the tension on the governor spring, said means comprising a socket extending longitudinally through the shaft and ter- minating at the end thereof.
37. A steam turbine comprising a shaft, 95 a sleeve inclosing it and a turbine wheel mounted on the sleeve, a governor entirely inclosed within the wheel and shaft, and adapted to move the sleeve slidably on the shaft.
38. A steam turbine comprising a shaft 100 mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally along the shaft to govern the turbine.
39. A steam turbine comprising a shaft 105 mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally 110 along the shaft to govern the turbine, means for adjusting the governor without the exposure of any of the governor parts.
40. A steam turbine comprising a shaft 115 mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally 120 along the shaft to govern the turbine, the shaft provided at one end with means where- by to compensate for unequal expansion and

contraction of the shaft and surrounding parts.

41. A steam turbine comprising a shaft mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally along the shaft to govern the turbine, means for adjusting the governor without the exposure of any of the governor parts, the shaft provided at one end with means whereby to compensate for unequal expansion and contraction of the shaft and surrounding parts.

42. A steam turbine comprising a shaft mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally along the shaft to govern the turbine, the governor having a spring and means for adjusting the tension thereon without exposing any of the governor parts.

43. A steam turbine comprising a shaft mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally along the shaft to govern the turbine, the governor having a spring located within the shaft and means accessible through the end of the shaft for adjusting the tension on the governor spring.

44. A steam turbine comprising a shaft mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally along the shaft to govern the turbine, means for adjusting the governor without the exposure of any of the governor parts, said means comprising a socket extending longitudinally through the shaft and terminating at the end thereof.

45. A steam turbine comprising a shaft mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally along the shaft to govern the turbine, the governor having a spring and means for adjusting the tension thereon without exposing any of the governor parts, and means comprising a socket extending

longitudinally through the shaft and terminating at the end thereof.

46. A steam turbine comprising a shaft mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally along the shaft to govern the turbine, the governor having a spring located within the shaft and means accessible through the end of the shaft for adjusting the tension on the governor spring, said means comprising a socket extending longitudinally through the shaft and terminating at the end thereof.

47. A steam turbine comprising a shaft mounted for rotation and held against longitudinal movement, a sleeve mounted slidably on the shaft but held against rotation with respect thereto, a turbine wheel mounted on the sleeve and a governor adapted to move the sleeve and wheel longitudinally along the shaft to govern the turbine, the governor having a spring and means for adjusting the tension thereon without exposing any governor parts, a plug associated with the spring and movable within the shaft, lugs projecting therefrom through the shaft to engage the sleeve.

48. A steam turbine comprising a shaft mounted for rotation and held against longitudinal movement, a sleeve mounted slidably on the shaft but held against rotation with respect thereto, a turbine wheel mounted on the sleeve and a governor adapted to move the sleeve and wheel longitudinally along the shaft to govern the turbine, the governor having a spring, a plug associated with the spring and movable within the shaft, lugs projecting therefrom through the shaft to engage the sleeve.

49. A steam turbine comprising a shaft mounted for rotation and held against longitudinal movement, a sleeve mounted slidably on the shaft but held against rotation with respect thereto, a turbine wheel mounted rigidly on the sleeve and a governor adapted to move the sleeve and wheel longitudinally along the shaft to govern the turbine, the governor having a spring located within the shaft and means accessible through the end of the shaft for adjusting the tension on the governor spring, a plug associated with the spring and movable within the shaft, lugs projecting therefrom through the shaft to engage the sleeve.

50. A steam turbine comprising a shaft mounted for rotation and held against longitudinal movement, a sleeve mounted slidably on the shaft but held against rotation with respect thereto, a turbine wheel mounted rigidly on the sleeve and a governor adapted

to move the sleeve and wheel longitudinally along the shaft to govern the turbine, the governor having a spring and means for adjusting the tension thereon without exposing 5 any of the governor parts, said means comprising a socket extending longitudinally through the shaft and terminating at the end thereof, a plug associated with the spring and movable within the shaft, lugs 10 projecting therefrom through the shaft to engage the sleeve.

51. A steam turbine comprising a shaft mounted for rotation and held against longitudinal movement, a sleeve mounted slidably 15 on the shaft but held against rotation with respect thereto, a bucket wheel mounted rigidly on the wheel and a governor adapted to move the sleeve and wheel longitudinally along the shaft to govern the turbine, the 20 governor having a spring located within the shaft and means accessible through the end of the shaft for adjusting the tension on the governor spring, said means comprising a socket extending longitudinally through the 25 shaft and terminating at the end thereof, a sliding plug associated with the spring and 30 slideable within the shaft to engage the sleeve and hold it against rotary movement with respect to the shaft.

52. A steam turbine comprising a shaft, a sleeve inclosing it and a turbine wheel mounted on the sleeve, a governor entirely inclosed within the shaft and wheel, and adapted to move the sleeve slidably on the 35 shaft, governor weights entirely inclosed within the wheel and a connection between the weights and the shaft extending through the sleeve, the weights being free to rotate with respect to the shaft in a plane containing the shaft but held against longitudinal 40 movement with respect thereto at the point where they engage the shaft.

53. A steam turbine comprising a shaft mounted for rotation and held against longitudinal movement, a sleeve mounted slidably 45 on the shaft but held against rotation with respect thereto, a turbine wheel mounted on the sleeve and a governor adapted to move the sleeve and wheel longitudinally along the shaft to govern the turbine, governor 50 weights entirely inclosed within the wheels and a connection between the weights and the shaft extending through the sleeve, the weights being free to rotate with respect to the shaft in a plane containing the shaft but held against longitudinal 55 movement with respect thereto at the point where they engage the shaft.

54. A steam turbine comprising a shaft 60 mounted for rotation and held against longitudinal movement, a sleeve mounted slidably on the shaft but held against rotation with respect thereto, a turbine wheel mounted on the sleeve and a governor adapted to 65 move the sleeve and wheel longitudinally

along the shaft to govern the turbine, means for adjusting the governor without the exposure of any of the governor parts, governor weights entirely inclosed within the wheels and a connection between the weights 70 and the shaft extending through the sleeve, the weights being free to rotate with respect to the shaft in a plane containing the shaft but held against longitudinal movement with respect thereto at the point where they 75 engage the shaft.

55. A steam turbine comprising a shaft mounted for rotation and held against longitudinal movement, a sleeve mounted slidably 80 on the shaft but held against rotation with respect thereto, a turbine wheel mounted on the sleeve and a governor adapted to move the sleeve and wheel longitudinally along the shaft to govern the turbine, the governor having a spring and means for adjusting the 85 tension thereon without exposing any of the governor parts, governor weights entirely inclosed within the wheel and a connection between the weights and the shaft extending through the sleeve, the weights being free to 90 rotate with respect to the shaft in a plane containing the shaft but held against longitudinal movement with respect thereto at the point where they engage the shaft.

56. A steam turbine comprising a shaft 95 mounted for rotation and held against longitudinal movement, a sleeve mounted slidably on the shaft but held against rotation with respect thereto, a turbine wheel mounted on the shaft and a governor adapted to move 100 the sleeve and wheel longitudinally along the shaft to govern the turbine, the governor having a spring located within the shaft and means accessible through the end of the shaft for adjusting the tension on the governor 105 spring, governor weights entirely inclosed within the wheels and a connection between the weights and the shaft extending through the sleeve, the weights being free to rotate with respect to the shaft in a plane containing the shaft but held against longitudinal 110 movement with respect thereto at the point where they engage the shaft.

57. A steam turbine comprising a shaft mounted for rotation and held against longitudinal movement, a sleeve mounted slidably 115 on the shaft but held against rotation with respect thereto, a turbine wheel mounted on the sleeve and a governor adapted to move the sleeve and wheel longitudinally along the shaft to govern the turbine, means for adjusting the governor without the exposure of any of the governor parts, said means comprising a socket extending longitudinally through the shaft and terminating at 120 the end thereof, governor weights entirely inclosed within the wheels and a connection between the weights and the shaft extending through the sleeve, the weights being free to rotate with respect to the shaft in a 125 130

plane containing the shaft but held against longitudinal movement with respect thereto at the point where they engage the shaft.

58. A steam turbine comprising a shaft 5 mounted for rotation and held against longitudinal movement, a sleeve mounted slidably on the shaft but held against rotation with respect thereto, a turbine wheel mounted on the sleeve and a governor adapted to 10 move the sleeve and wheel longitudinally along the shaft to govern the turbine, the governor having a spring and means for adjusting the tension thereon without exposing any of the governor parts, said means 15 comprising a socket extending longitudinally through the shaft and terminating at the end thereof, governor weights entirely closed within the wheels and a connection 20 between the weights and the shaft extending through the sleeve, the weights being free to rotate with respect to the shaft in a plane containing the shaft but held against longitudinal movement with respect thereto at the point where they engage the shaft.

25 59. A steam turbine comprising a shaft mounted for rotation and held against longitudinal movement, a sleeve mounted slidably on the shaft but held against rotation with respect thereto, a turbine wheel mounted on the sleeve and a governor adapted to 30 move the sleeve and wheel longitudinally along the shaft to govern the turbine, the governor having a spring located within the shaft and means accessible through the end 35 of the shaft for adjusting the tension on the governor spring, said means comprising a socket extending longitudinally through the shaft and terminating at the end thereof,

governor weights entirely inclosed within the wheels and a connection between the 40 weights and the shaft extending through the sleeve, the weights being free to rotate with respect to the shaft in a plane containing the shaft but held against longitudinal movement with respect thereto at the point where 45 they engage the shaft.

60. In a steam turbine a shaft, a rotor axially movable thereon, and yielding means for resisting its movement, governor weights socketed loosely on the shaft at their inner 50 ends and engaging the rotor at their outer ends, the center of gravity of said weights being located in a plane axially removed from the plane in which their outer ends are located. 55

61. In a steam turbine a shaft, a rotor axially movable thereon, and yielding means for resisting its movement, governor weights socketed loosely on the shaft at their inner 60 ends and engaging the rotor at their outer ends, the center of gravity of said weights being located in a plane axially removed from the plane in which their outer ends are located.

62. A steam turbine comprising a smooth 65 shaft, a hollow rotor mounted thereon, having a smooth cylindrical surface, a hollow cylindrical flange projecting laterally from one of the surfaces of the drum and in line with the periphery thereof and turbine 70 buckets disposed within the flange whereby the motive fluid passes radially through said flange.

Signed at Chicago, county of Cook, and State of Illinois, this 14th day of May, 1920. 75

CHARLES W. DAKE.
